MULTIPOLAR CIRCUIT MAKER AND BREAKER

Emile André Berthier, Rte. National, Villefranche-sur-Saône (Rhône), France

Filed Apr. 10, 1961, Ser. No. 102,064

Claims priority, application France Apr. 13, 1960

4 Claims. (Cl. 200—89)

The use of three-phase current under 220 volts and frequencies ranging between 50 and 1,000 cycles in the distributing mains on board aircrafts has led to investigating the structure of multipolar circuit breaking switches protecting the apparatus on board when operating at high altitudes.

The use which is becoming more and more frequent of 380 volt voltages in cities and chiefly in small localities where an increasing number of small three-phase low power motors are used makes it also necessary to resort to protecting circuit-breaking switches.

These various applications require the use of an arrangement satisfying on the one hand, the wish of the fitter as concerns bulk, rigid securing and the like, and on the other hand, it should satisfy through its electrical and mechanical data the requirements of the operator as to maximum reliability.

Small power unipolar circuit-breaking switches are already known which satisfy such conditions. Such a switch includes a setting knob, a movable releasing knob adapted to move inside said setting knob and a yielding blade carrying the movable contact-piece and which is locked in its operative position by a locking lever pivotally carried by the setting knob which is locked in its turn by a catch at such a moment.

The releasing knob acts then directly on an upper extension of the pivoting locking lever through the agency of a sloping surface formed on said knob.

Now in my improved circuit-breaking switch according to my invention, the setting is controlled by a knob rigid with means, such as lateral arms extending above the setting knobs of the mechanisms controlling a number of associated circuit-breaking switches, the number of which is equal to that of the number of circuits to be controlled simultaneously, while the release is controlled by a bar adapted to be shifted rectilinearly and transversely with reference to the associated circuit-breakers each of which is provided with its own control lever, holding its yielding contact-piece in its operative position and engaging said bar of which any shifting produced by one of said circuit-breakers is simultaneously transmitted to all the other circuit-breakers.

The conditions to be satisfied by such an arrangement may be summarized as follows:

It should have a reduced weight;

It should occupy a volume as small as possible;

Its adjustment should be accurate, chiefly for low intensities of a few milliamperes and it is therefore necessary for said circuit-breaker to be adjustable.

The operation of the circuit-breaker should not be disturbed by the modifications in room temperature as long as said temperature ranges between -30° C. and $+90^{\circ}$ C. To this end, the circuit-breaker should be compensated against the action of temperature.

Its design should not allow any arcing between the poles of the phases under the action of a reduction in pressure corresponding to a 50 mm. mercury column;

The appliance should allow a manual setting and release;

It should include one or more small switches for low voltages inserted independently of the protecting circuits, with a view to signalling the location of the contact-pieces and possibly, a remote control;

It should be readily removable in order to further a speedy exchange of nominal intensities;

2

Its set and released positions should be controlled from a distance through the opening or closing of an electric circuit;

If it is associated with a remote control, its operation should be accompanied by as little noise as possible;

My invention has for its object a multipolar circuit-breaking switch adapted to be controlled manually and from a distance by an electric circuit.

The accompanying drawing illustrates diagrammatically several embodiments of a tripolar circuit-breaking switch according to my invention and which I will term hereinafter a "circuit-breaker". In said drawings:

FIG. 1 is a vertical cross-section of the appliance;

FIG. 2 is a partial perspective view limited to the means correcting the duration of release and the member allowing manual release;

FIG. 3 is a plan view of means for the general and individual adjustment of the bimetallic blade associated with the releasing bimetallic blade to compensate for the action of varying temperature;

FIGS. 4 and 5 are elevational views showing in two different positions the movable contact-piece adapted to signal or to control at a distance respectively the opening and the closing of the contact-making circuit-breaker;

FIG. 6 illustrates a modification of said arrangement wherein the signalling circuit is closed when the main contact-piece is closed;

FIG. 7 is a perspective view showing a circuit-breaking block adapted to be removed from its pedestal

FIGS. 8 and 9 are views showing the remote electric control member for the circuit-breaker, respectively in vertical cross-section through line 8—8 of FIG. 9 and line 9—9 of FIG. 8;

FIG. 10 is a perspective view of a modification of the means adjusting the relative position of the compensating bimetallic blade with reference to the other releasing bimetallic blade;

FIGS. 11 and 12 are two different wiring diagrams for the remote control;

FIG. 13 is on a much larger scale, a longitudinal cross-section of the individual adjusting means for the position of the compensating bimetallic blade;

FIGS. 14 and 15 are perspective views and a cross-sectional view through line 15—15 of FIG. 14 of the arrangement of the small masses balancing the movable releasing bar.

Turning to FIG. 1, it is apparent that the same pedestal 2 carries in juxtaposition three circuit-breaking mechanisms of a known type. Said mechanisms housed in individual casings 3, 4 and 5 are separated from one another by the partitions 7 and 8 arranged in staggered formation with reference to the adjacent casings 3 and 5 respectively (FIG. 1) so as to provide long lines of leak and to avoid any arcing at an altitude corresponding to a pressure of the mercury column approximating 50 mm. or above.

Each of the insulating casings 3, 4 and 5 housing the corresponding mechanisms provides merely the passage of the cooperative control knob, respectively 9, 10 and 11. The position of the latter is controlled by the central pusher knob 10 provided with two arms 14 and 15 extending perpendicularly to the axis of shifting of said pusher-knob with which said arms are integral while they extend at the same level as the latter.

The operation of said circuit-breaker is as follows:

The contact-piece of the three elementary circuit-breaker mechanisms are engaged simultaneously by depressing the master knob 16 which slides coaxially with reference to the pusher-knob against the action of the spring 17 so as to transmit to the latter the thrust received by it through the agency of said spring 17 which is gauged with a view to compensating the antagonistic

stress exerted by the spring acting on the knob 10 and also by the springs acting on the knobs 9 and 11 carried along by the arms 14 and 15 rigid with said knob 10.

The manual release is performed by exerting a pressure which is larger than that originally exerted on the knob 16 when the pusher-knob 10 and the small rod carrying it are already in their lowermost position. The spring 17 is then compressed under the action of the pressure exerted on the knob 16 so that the end of the slope 18 at the inner end of said rod which acts after the manner of a wedge, causes then the lever 19 to rock round the pivot 21 in the knob 10 in the direction of the arrow 20.

Consequently, the end 22 of the lever 19 extending downwardly so as to engage a small bar 23 adapted to be shifted along a straight transverse line, drives said bar along in the direction of said arrow whereby the ends 25 and 26 of the levers 27 and 28 forming part of the circuit-breakers located to either side of the central circuit-breaker 10 and engaging the small bar 23 are also shifted in the same direction, said levers 27 and 28 being subjected to the control exerted by the corresponding knobs 9 and 11 respectively when depressed. The release by the bar 23 of the levers 27 and 28 releases simultaneously the yielding contact-carrying blades respectively 29, 30 and 31.

The automatic release is produced electrically in the following manner:

If one of the bimetallic blades 33, 34 and 35 cooperating with one of the elementary circuit-breakers or if one of the electromagnetic arrangements 36, 37 or 38 forming the releasing elements in the mechanisms of the elementary circuit-breakers is subjected to the action of an excess intensity or of a short circuit, this leads to a shifting of the ends 25, 22 or 26 of the corresponding levers 27, 19 or 28 pivotally carried by the corresponding pusher-knobs, said shifting which is produced simultaneously on the three circuit-breaking mechanisms by the shifting of the small bar 23 ensures their simultaneous release.

The spring 39 returns then the small bar 23 into its starting position so as to allow the reengagement or resetting of the three mechanisms.

The three-phase circuit-breaking switch described hereinabove is provided with a single knob having a double part to play, that of engaging and releasing by hand the switch.

However certain operators prefer being supplied with two separate control knobs, respectively for starting and for stopping, chiefly in the case of the control of machine tools. In this case (FIG. 2) the manual operation is as follows: a knob 41 passing through the insulating hood 6 carries a coaxial rod 43 terminating at its lower end with a slope 44, adapted to urge forwardly a flap 45 which is thus caused to pivot in the direction of the arrow 46 round its trunnions 47 and 48 while carrying along with it the bimetallic blade 44 of which the free end 50 acts on the lever 19 (FIG. 1) so as to produce the release of the circuit-breaker as disclosed hereinabove.

The pusher-knob 41 is urged back into its inoperative position by the spring blade 51 which shifts rearwardly the flap 45 in the direction of the arrow 52.

Since the three circuit-breaking mechanisms are associated inside a common hood, it is necessary to provide for a very accurate adjustment of the operation of the corresponding bimetallic blades 33, 34 and 35, chiefly when the circuit-breaker is to open circuits fed with small nominal intensities of say a few ten milliamperes for instance. Said adjustment is obtained (FIG. 2) by adjusting the position of a screw 53 in a stationary metal member 54 provided with a signalling member 55 at its outer readily accessible end.

The spring blade 51 urges the flap 45 rearwardly against the screw 53 and by rotating the signalling mem-

ber 55 clockwise or anticlockwise, the flap 45 subjected to the action of the spring 51 describes the arc of a circle, the center of which passes through the aligned trunnions so as to bring the free end of the bimetallic blade 50 into the position which is the most favorable with a view to obtaining the desired adjustment with reference to the releasing levers respectively 27, 19 and 28.

The same results may be obtained as concerns the desired adjustment by acting on the location of the bimetallic blade 34 through the arrangement illustrated in FIG. 10 to be now described hereinafter.

A flap 101 revolvably carried by the trunnions 47 and 48 is rigid at its lower end with a spring 102 to which are secured the bimetallic blade 34 and also a compensating bimetallic blade 51 which cannot be replaced in the present case by a spring. A tail-piece 104 on said flap 101 carries a screw 105 the end of which engages the flap 101 carrying the bimetallic blade 34. By screwing to a varying extent the screw 105 into the tail-piece 104, it is therefore possible to deform the flap 101 and to obtain a more or less considerable shifting of the free end 50 of the bimetallic blade 34 with reference to the compensating bimetallic blade 51.

If the multipolar circuit-breaker is to operate in premises in which the temperature range between -30° C. and $+90^{\circ}$ C., it is necessary to provide for compensation against temperature modifications in order to obtain an automatic correction upon a thermic release produced by a bimetallic blade. The arrangements provided for this purpose in the appliance described are as follows: the elementary mechanisms are compensated individually; they are housed in the same casing and should be adjusted accurately with reference to one another so as to ensure uniform duration of release.

This result is obtained by resorting to three screws 56, 57 and 58 (FIG. 3) inside which extends longitudinally an insulating rod 66 revolving inside said screws with slight friction (FIG. 13). The three screws 56, 57 and 58 include each a flat head 59, 60 and 61 (FIG. 3) provided with recesses 60a perpendicular to the axis of its threaded section, said heads being slightly clamped between two partitions 5-6, 4-8 or 7-3 in order to provide a slight friction. The screws 56, 57 and 58 threadedly engage the bimetallic blades 63, 64 and 65 respectively and it is readily apparent that by holding fast to the insulating rod 66, it is possible to act individually on the relative position of each bimetallic blade by rotating the corresponding screw 56, 57 or 58 in the desired direction by means of a stem engaging one of the recesses 60a in the head of the screw to be operated. The general adjustment of the blades is obtained by turning the head of the screw 67 which is rigid with the insulating rod 66.

In order to produce a remote signal showing the circuit-breaker has been actually released, the mechanism of at least one of the elementary circuit-breakers may carry contact-pieces of the type illustrated in FIGS. 4 to 6.

A movable contact-piece blade 69 illustrated in FIG. 4 in its release position closes the auxiliary contact-pieces 71 and 72 of an independent circuit. The same contact-carrying blade 69 is illustrated in FIG. 5 in its set position with the contact-pieces 71 and 72 open.

Lastly, in the modification illustrated in FIG. 6, the contact-carrying blade 69 is shown in its set position with the contact-pieces 73 and 74 closed because, in this modification, said contact-pieces are closed for a position which is the reverse of that illustrated in FIGS. 4 and 5.

The arrangements resorted to for providing a circuit-breaker which is removable with reference to its pedestal are illustrated in FIG. 7 where the pedestal 75 shows only three apparent contact-pieces, the other contact-pieces being arranged similarly at the other end of the pedestal which is not illustrated. When the hood 6 covering the circuit-breaker is fitted inside the pedestal 75, the contact-pieces 77, 78 and 79 engage the corresponding contact-pieces 81, 82 and 83 of the pedestal, the casing 76 sliding in the direction of the arrow 84.

Such multipolar or merely unipolar circuit-breakers may also be provided with remote electric control means. To this end, there is provided at the lower end of an insulating pedestal a housing 85 (FIGS. 8 and 9) inside which are positioned:

At its lower end, at least two half-annuli 86 and 87 of magnetic material having preferably its molecules set in a predetermined direction and a winding 88 of insulated wire inside which is housed one of the arms 86a and 87a of each of said half-annuli.

At the upper end of said housing are positioned two further half-annuli 89 and 90 made of the same metal as the half-annuli 86 and 87, said half-annuli 89 and 90 being carried by a movable carrier 91 adapted to slide inside said housing 85, which carrier 91 is rigid with the rod 92 controlling the pusher-knob 93.

When the winding 88 is energized by an impulse of electric current, the magnetic field thus produced attracts the movable half-annuli 89 and 90, so that they sink into contact with the stationary half-annuli 86 and 87. During this movement, the carrier 91 of the movable half-annuli draws along with its the pusher-knob controlling rod 92, so as to provide for the closing of the switch constituted by the contact-pieces 94 and 94a.

To cut out the noise produced by the engagement between the pairs of half-annuli, the periphery of the movable carrier 91 may be provided with a packing 95 of leather or the like material matching the outline of the carrier in the same manner as the packing provided for a pump piston. When the winding 88 is energized, the movement of the movable half-annuli 89 and 90 attracted by the stationary half-annuli 86 and 87 in the direction illustrated by the arrow 96 compresses the air enclosed inside the gap between the pairs of half-annuli whereby the shock between the cooperating half-annuli is braked at the end of the travel of said movable half-annuli. An adjustment of said braking action is obtained by controlling through the agency of the grooved screw 97, the port 98 through which the compressed air is allowed to escape.

In order that the circuit-breaker may be released and reengaged from a distance, it is possible to cut out in the appliance the catch engaging the small rod 107 (FIG. 8) similar to that rigid with the knob 10 (FIG. 1) and the engagement of the contact-pieces 94 and 94a is maintained solely through the energization of the winding 88.

Said result may be obtained, in particular, by resorting to one of the wiring diagrams described hereinafter:

In the wiring diagram of FIG. 11, the closing of the switch 108 produces the energization of the winding 88. The circuit-breaker is thus engaged until said switch 108 is again opened.

In the diagram illustrated in FIG. 12, the circuit-breaker includes a further contact-piece of the type described with reference to FIGS. 4 to 6. By closing at a distance the switch 109 through the connections 111, 112 and 113, the winding 88 is energized, which controls the contact-pieces of the circuit-breaker 110 and, in particular, the contact-piece 114. The winding 88 continues being energized, even after the opening of the switch 109 through the connections 115 and the switch 116 which is held permanently closed by the spring 117.

To release by hand the circuit-breaker 110, it is therefore necessary to open the switch 116 by depressing the corresponding pusher-knob 118 against the spring 117.

The multipolar circuit-breaker described is an apparatus of a reduced weight occupying a very reduced volume. Its adjustment is very accurate, even in the case of very small intensities. Its operation cannot be influenced by room temperature as long as the latter ranges between -30° C. and $+30^{\circ}$ C. which are the limits consistent with the possibilities of an adjustment of its parts compensating modifications in temperature. Its casing provided with a baffle system cuts out any risk of arcing between the poles or the phases under conditions of pres-

sure which are even considerably lower than normal pressure.

As described hereinabove, my improved circuit-breaker may be released and set manually or electrically even from a distance and it includes to this end, if desired, means for signalling at a distance the location of its contact-pieces.

Although the operation of the appliance is highly satisfactory when it is adapted to control stationary plants, the case may not be the same when it is subjected directly or through the agency of its pedestal to sudden shocks or displacements. As such a moment, the inertia of the small bar 23 (FIG. 1) may lead to a transverse shifting of the latter with reference to its pedestal and this may lead in its turn to an untimely release of the contact-pieces of the circuit-breaker as a consequence of the movement imparted by said small bar 23 to the lever ends 25, 22 and 26 engaging it.

In order to cut out this drawback when the circuit-breaking and making system is positioned on a movable part such as an aircraft, compensating weights are fitted in the following manner: round a stud 120 carried by the pedestal 2 of the appliance, there is pivotally secured a lever 121, of which one end 122 carries a weight 133, while its other end 124 engages a recess 125 provided in the small bar 23.

A single weight which is sufficiently heavy may ensure the desired operation, but the reduced volume available in the pedestal of the appliance leads to preferring possibly inserting two such weights with a view to obtaining the desired result.

Said weights operate as follows: at the moment at which the pedestal 2 of the apparatus is subjected to a shock, the stud 120 rigid with said pedestal transmits the shocks to the lever 121 carrying the weight 133 and engaging the small bar 23. By reason of the balance between the weights corresponding, on the one hand, to the small bar 23 and lever ends 25, 22, 26 engaging it and, on the other hand, to the small weights 133, the balanced system is not disturbed by the shocks and follows as a unit the movement of the pedestal 2, and the absence of any shifting of the bar 23 with reference to said pedestal 2 cuts out the risk of any release.

Obviously, the invention is not limited to the sole embodiment of the three-pole circuit-breaker which has been described hereinabove and it covers all the modifications thereof, whatever may be the number of separate elementary circuit-breakers associated inside the same casing and whatever may be the detail structure of the means serving for the simultaneous transmission to the different pusher-knobs providing for the engagement of the circuit-breaker of the thrust to which the main knob is subjected or for shifting simultaneously the releasing levers when one of them has been released.

What I claim is:

1. A multipolar circuit-breaker comprising a plurality of juxtaposed elementary circuit-breakers including each an elementary control knob, a yielding contact-making blade adapted to be set by the control knob in its operative position, a lever pivotally secured to said knob and holding the contact-making blade in its controlled operative position, and temperature-sensitive means releasing said lever, a common bar extending across the lower ends of all the levers and engaging said ends to ensure their simultaneous rocking upon release of one of them to provide the simultaneous release of all the elementary circuit-breakers, a casing enclosing all the elementary circuit-breakers and common bar means including a master control knob controlling simultaneously the different elementary control knobs, a weighted lever pivotally secured to the casing and engaging the common bar to balance the system of levers on the latter thereby to constrain said common bar to follow any sudden movement of the casing.
2. A multipolar circuit-breaker comprising a plurality

of juxtaposed elementary circuit-breakers including each an elementary control knob, a yielding contact-making blade adapted to be set by the control knob in its operative position, a lever pivotally secured to said knob and holding the contact-making blade in its controlled operative position, and an electromagnet including a winding and an armature controlled by the winding and rigid with the control knob to make the latter release the lever, a common bar extending across the lower ends of all the levers and engaging said ends to ensure their simultaneous rocking upon release of one of them to provide the simultaneous release of all the elementary circuit-breakers, a casing enclosing all the elementary circuit-breakers and common bar and means including a master control knob controlling simultaneously the different elementary control knobs.

3. A multipolar circuit-breaker comprising a plurality of juxtaposed elementary circuit-breakers including each an elementary control knob, a yielding contact-making blade adapted to be set by the control knob in its operative position, a lever pivotally secured to said knob and holding the contact-making blade in its controlled operative position, a magnetic circuit including a stationary section and a section rigid with the control knob and adapted to move towards and away from the stationary section, each section being constituted by two adjacent half-annuli, the cooperating half-annuli in the two sections facing each other to form upon engagement of the two sections, complete adjacent annuli, the axes of which are parallel and perpendicular to the direction of movement of the movable section, an electromagnetic winding surrounding the adjacent portions of the half-annuli on the stationary winding and urging, when energized, the movable section towards it and making the control knob release the lever, a common bar extending across the lower ends of all the levers and engaging said ends to ensure their simultaneous rocking upon release of one of them to provide the simultaneous release of all the elementary circuit-breakers, a casing enclosing all the elementary circuit-breakers and common bar, and means including a master control knob

controlling simultaneously the different elementary control knobs.

4. A multipolar circuit-breaker comprising a plurality of juxtaposed elementary circuit-breakers including each an elementary control knob, a yielding contact-making blade adapted to be set by the control knob in its operative position, a lever pivotally secured to said knob and holding the contact-making blade in its controlled operative position, a magnetic circuit including a stationary section and a section rigid with the control knob and adapted to move towards and away from the stationary section, each section being constituted by two adjacent half-annuli, the cooperating half-annuli in the two sections facing each other to form, upon engagement of the two sections, complete adjacent annuli, the axes of which are parallel and perpendicular to the direction of movement of the movable section, a shock-damping packing along the periphery of one of the sections adapted to engage the other section upon impact between the sections, an electromagnetic winding surrounding the adjacent portions of the half-annuli on the stationary winding and urging, when energized, the movable section into movement and making the control knob release the lever, a common bar extending across the lower ends of all the levers and engaging said ends to ensure their simultaneous rocking upon release of one of the elementary circuit-breakers and common bar, and means of them to provide the simultaneous release of all the including a master control knob controlling simultaneously the different elementary control knobs.
